UNITED STATES PATENT OFFICE.

JAMES H. MUNRO, OF NEWARK, NEW JERSEY, ASSIGNOR OF ONE-HALF
TO JOHN MILTON VAN ORDEN, OF NEWARK, NEW JERSEY.

SLATING.

SPECIFICATION forming part of Letters Patent No. 769,664, dated September 6, 1904.

Original application filed October 30, 1903, Serial No. 179,221. Divided and this application filed March 24, 1904.
Serial No. 197,782. (No model.)

To all whom it may concern:

Be it known that I, JAMES H. MUNRO, of Newark, New Jersey, have invented certain Improvements in Slating, of which the following description, in connection with the accompanying drawings, is a specification, like figures on the drawings designating like parts.

This invention relates to building construction, and has for its object the production of covering means capable of use to great advantage as a roofing material, but also applicable to walls and in other situations where my improvements are rendered available and desirable by their nature.

In perfecting my invention I have made possible the use of members of roofing-slate of much smaller dimensions than are required ordinarily, redeeming from the waste-pile large quantities of this material, which, accordingly, I prefer to utilize, but to which I do not, of course, limit myself.

The chief feature of my invention is a light, waterproof, fireproof, and air-tight covering made out of exceptionally thin slate cut up into unusually small sizes to be grouped together and cemented onto a carrier of paper or other suitable fabric or material as a unit and cemented onto the roofs or walls of a house by a waterproof and adhesive cement, making the finished surface of this thin slate present a flat plane. This air-tight and waterproof slate construction cannot be obtained by the present method of nailing slates to a roof or wall, in which each slate overlaps others tilted at an angle to carry the water from one to the other and prevent the rain getting beneath. When one of these slates works loose from its fastening by the action of the elements, as very often occurs, it slips out of its position and falls to the ground, not only to the danger of the passer-by, but leaving the open joint of the underlying slates uncovered and unprotected from the storm, letting the water penetrate and do damage inside.

Another cause for detachment of slates from their fastening when laid by the present method of nailing slates one over the other is

the fact that slate by its own nature attracts and draws moisture, although it does not absorb it, and in winter it accumulates in the air-space below each and every slate set by the present method of lapping the slate members over each other and very often freezes, expanding and cracking the slate, which slides off when the thaw comes. These slate members weigh from three to seven pounds each, according to the size of the slate used, and many fatal accidents occur through detachment of the slates and their blowing off the roof. To eliminate this danger, I prefer to split or cleave the slate exceptionally thin and reduce the size of the members to about one-twentieth part the size of the average slate members now used and about one-fortieth part in weight and then cement these to their support, either directly upon the boards or upon a lining of slates or other material, to be described, with a waterproof and preferably an elastic cement or secure them to the support by other suitable fastening means.

Another object in reducing the size of the slate into small members is to overcome the uneven surface of the natural cleavage of slate, which is in many cases so pronounced as to prevent its being practicable to embed large slates into a thin bedding of cement without having air-pockets or vacuum portions, which would make the slates break when walked upon and unsafe by reason of their thinness.

To summarize, I propose to cut the slate into small members to insure solidity and provide a flatter surface, with a corresponding economy in weight and material.

I prefer to assemble these small slates at the quarry into sheets or rolls, cementing to their surfaces or otherwise securing paper or other fabric or means to hold them together as a unit previous to transporting them to the place where they are to be used, and while I claim as new and original the cementing of a layer of small slate members assembled as a unit directly to the roofing-boards or to a layer or layers of tar-paper or the like I prefer

to first cover the roof or wall with a layer of relatively long narrow slate members, either assembled together as a unit or secured to the roof or wall piece by piece to form a foundation or lining for the top layer of slate members.

The various features of my invention are illustrated and described fully in the accompanying drawings and specification and pointed out in the claims.

In the drawings, Figure 1 illustrates in perspective a portion of a roof to which has been applied sheets or sections of covering members mounted on holding means in accordance with my invention. Fig. 2 illustrates in side elevation a post to which my invention has been applied, parts being broken away to show the construction in section. Figs. 3 and 4 show in section composite slates or units comprising a plurality of layers, to be described more fully hereinafter. Figs. 5 to 8, inclusive, are views, on an enlarged scale, of slate members having rustic edges and laid in slightly-different relative positions. Fig. 9 shows in plan and vertical section, respectively, views of sheets or sections of a modified form, while Fig. 10 shows in plan and horizontal section, respectively, the same sheets assembled.

In the embodiment of my invention selected for description and illustration as a convenient form to enable a ready and complete understanding of my improvements, referring to Fig. 1, the reference-numeral 1 designates the individual covering members, which in the instance shown appear as relatively narrow pieces of slate assembled with abutting edges and constituting a substantially integral slate layer to be laid as a unit, being provided with a lining-layer of holding means 2, which may conveniently be tar-paper or other fabric or suitable material, an intervening layer of bituminous or other cement 3 being preferably utilized to secure the members 1 in place and to act as a waterproof layer. Such sections may be supported in any convenient manner, and in Fig. 1 metal T-bars 4 are shown supported by rafters 5, the frames 6 of the T-bars having a bedding of cement 7 for the ends of the slates constituting the lateral edges of the sections or units.

An adaptation of the slating with elongated members to curved surfaces is shown in Fig. 2, in which the reference-numeral 8 designates a post, which for the sake of illustration may be considered as a pile to be driven in waters containing the teredo or other agencies destructive to piles. In this figure the slate members 9 are illustrated as mounted on holding means 10, taking the form in this instance of a sheet of tar-paper, for which any other suitable fabric or holding means may be substituted, as desired and found convenient. The slates are secured to the tar-paper pref-

erably by a layer of cement 11, bituminous or otherwise, and the holding means can be secured by nails 12 or cement 13, or both, to the pile or post, and I contemplate a plurality of layers of such protective sheets in concentric or spiral relation, according as it is found more convenient to apply a protective lining in the form of sheets or rolls, in which latter form the slate lining may be shipped very advantageously, and these same rolls of slate lining will be found probably most convenient for application to a roof, although in some situations the sheets would be preferred.

Fig. 3 shows two layers of slate members 14 with an intervening layer of tar-paper or the like 15, to which the slates are preferably secured by cement 16.

Fig. 4 shows a plurality of layers of slates 17, secured together by a layer 18, of cement, to form a composite slate or unit section similar to that shown in Fig. 3, but lacking the intervening layer of paper.

In Figs. 5 to 8, inclusive, I have shown sections or units of slates provided with a rustic finish beveled outwardly and upwardly, as appears clearly at 19 in Fig. 5, so that the edges of neighboring slates may be contiguous or closely adjacent and still present the rustic effect. When members with edges beveled in accordance with my invention are laid in cement, the cement cozes up during the process of laying, forms a key 20, and overlaps the adjacent beveled edges 19, and this part of the cement forms a bond, making this joint weather-tight and substantial and aiding to retain the members in place; but I have found that the cement, if elastic, does not interfere with their expansion or contraction nor with the flexibility of the unit, the expansion and contraction being reduced and distributed, owing to the large number of joints, the reference-numeral 21 designating the layer of cement, which in the instance illustrated secures the slate members to a layer of tar-paper 22, the whole forming a section to be laid as a unit in accordance with my invention. In Fig. 5 the members are laid with broken joints; in Fig. 6 with straight joints. In Fig. 7 diagonal members are shown, and in Fig. 8 elongated members.

In Fig. 9 members 23 are secured between layers 24 of paper or the like by cement 25, forming independent substantially integral slate layers to be laid as units, as shown in Fig. 10, where the two sheets are shown as laid in abutting relation.

Where the slate members are associated with a layer of elastic cement, either applied to single members or to the covering members assembled in sections, as illustrated in various figures of my application, an extremely important feature of my invention presents itself. Slate thus reinforced will not split or crack when a nail or the like is

driven through it and the thinner the slate thus reinforced the less is found to be the danger of splitting, and this capability, which is new with me and made possible only by my invention, enabling slate to be nailed without previous drilling of holes to receive the nails, and this capability differentiates the slate from vitreous tiles or other covering members of brittle material and seems to be due largely to the homogeneous quality of slate as a natural product reinforced by the cement.

Having thus illustrated and described fully my invention and the manner in which it may be carried into effect, it will be understood that I do not limit myself to the specific means illustrated and described herein nor in general otherwise than as set forth in my claims read in connection with this specification.

It is to be noted that this application has been divided from an application, Serial No. 179,221, filed October 30, 1903.

What I claim, and desire to secure by Letters Patent, is—

1. A covering for roofs or the like composed of a plurality of composite slates, each comprising a plurality of smaller pieces of slate having rustic edges chipped on an upwardly-turned bevel, and means to unite said pieces of slate in each composite slate, by setting in cement in such a manner that the cement oozes up into the joints between adjacent slates under the pressure of laying, forming a bond overlying said beveled edges, each said composite slate constituting a segregable unit to be set as such in a bedding of cement, substantially in the manner and for the purpose set forth.

2. A covering for roofs or the like composed of a plurality of composite slates having rustic edges chipped on an upwardly-turned bevel, each comprising a plurality of small pieces of slate and means to unite said pieces of slate in each composite slate by setting in elastic cement in such a manner that the cement oozes up into the joints between adjacent slates under the pressure of laying, forming a bond overlying said beveled edges, each said composite slate being set as a unit in a bedding of cement, substantially in the manner and for the purpose set forth.

3. A composite slate or section for roofing and similar purposes, comprising a plurality

of layers of relatively small members of slate joined together and to be laid as a unit, substantially as described. 55

4. A composite slate or section for roofing and similar purposes, comprising a plurality of layers of slate or similar material joined together and to be laid as a unit, one layer having broken joints relatively to the adjacent layer. 60

5. A composite slate or section for roofing or similar purposes, comprising a layer of slate and a plurality of layers of lining material, 65 said layer of slate being formed of a number of relatively small members of slate assembled with abutting edges and constituting a substantially integral slate-layer to be laid as a unit, substantially as described. 70

6. A waterproof, non-absorbent lining of the class described comprising a backing, and a plurality of elongated slate members cemented thereto by elastic cement and having outwardly-beveled edges to permit conformation 75 of said lining to the periphery of a post or the like, said lining comprising sections each to be laid as a unit, each section having a plurality of slates, substantially as described.

7. A covering for roofs or the like comprising slate members secured by a waterproof cement on both sides of a layer of paper or other fabric or suitable material, substantially as described. 80

8. As an article of manufacture slate or the like having a reinforcing layer of elastic cement applied thereto and serving to prevent splitting of said slate when pierced by a nail, said slate constituting a segregable unit for roofing or similar purposes. 85

9. A waterproof, non-absorbent lining of the class described comprising a backing and a plurality of elongated slate members cemented thereto and having beveled edges to permit conformation of said lining to the periphery 95 of a post or the like, said lining comprising sections each to be laid as a unit, each section having a plurality of slates, substantially as described. 90

Signed at New York, in the county of New York and State of New York, this 15th day of March, A. D. 1904.
